UNITED STATES PATENT OFFICE.

TIMOTHY DONOVAN, OF PORTSMOUTH, NEW HAMPSHIRE, ASSIGNOR TO MORLEY
BUTTON MANUFACTURING COMPANY, OF BOSTON, MASSACHUSETTS, A COR-
PORATION OF MAINE.

SHANK BUTTON.

Application filed January 11, 1921. Serial No. 436,417.

To all whom it may concern:

Be it known that I, TIMOTHY DONOVAN, citizen of the United States of America, and resident of Portsmouth, in the county 5 of Rockingham and State of New Hampshire, have invented new and useful Improvements in Shank Buttons, of which the following is a specification.

This invention relates to buttons of the 10 shank type such as are commonly used for accoutrements and leather articles, for over-gaiters and for shoes, and in other places requiring a small button of unusual strength and good appearance.

The requirements for such buttons heretofore have not been thoroughly satisfied, especially when the necessities of the use, or the trade necessities of ornamental quality, require a relatively thin or flat button.

15 Familiar examples in the prior art have comprised hemispherical or other thick buttons made of fibre, pearl, vitreous and other compositions and having wire shanks embedded in the body of the button, which 20 are unsatisfactory in appearance; and have also comprised buttons of hard material, such as vegetable ivory, having a headed wire shank inserted through a hole in the centre of the button. These latter are 25 satisfactory in appearance, but undurable, having a tendency to break diametrically, as induced by the leverage of the shank in the central drill hole.

I am aware that, in order to preserve the 25 appearance of flat buttons of the last-mentioned type and to improve their durability attempts have been made in the prior art to imitate their appearance; for instance, by the extensive manufacture of molded 40 composition buttons having the general form of the central-aperture headed-shank buttons and having a wire shank, the appearance of the shank head being achieved by a short rivet or pin having a head, inserted in the composition of the button, and not extending all the way through it. Such buttons were an improvement over the drilled-center shank buttons in durability, and well imitate their appearance, but are 45 exceedingly expensive to make and not sufficiently durable, the imitation center stud being a weakening factor.

A principal object of the present invention is to provide a button having a two- 55 ended wire shank embedded in the body

and having improved strength, and which also shall be provided with means producing the decorative effect of the headed-shank, drilled-center flat buttons mentioned above. Spot-center flat buttons are persistently called for by purchasers of the 60 class of articles for which they are an appropriate fastening, despite the demonstrated fact of the lack of durability of the drilled-and-headed shank form. When purchasers can be persuaded to examine the merits of molded flat buttons without the central shank, they prefer such buttons because of their undoubted better service, but some unthinking purchasers mistakenly 65 rely upon the appearance of the rounded metallic head of the central shank as a connotation of excellence. The present invention comprises a way of providing this 70 appearance without sacrificing the solidity of the button and without weakening the actual structure of the button, to the end of providing a button of greater strength which shall still have the popular appearance.

75 In the accompanying drawings,—

Figure 1 is a central section of a preferred type of one of the new buttons made according to this invention;

Figures 2 and 3 are similar views illustrating modifications;

Figure 4 is a face view of any of the forms shown showing the general appearance of the front face of the button;

Figure 5 is a similar section across one of 90 the perforated headed-shank buttons of the prior art; and

Figure 6 is a similar section of one of the imitation perforated shank buttons of the prior art.

95 Referring to Figure 1, the body of one of the buttons may comprise a generally flat solid having surfaces of revolution 2, 3, defining between them a projecting annular face ridge 4, which ridge surrounds a central depression 5 having a central rounded mound 6 formed therein. The mound 6 is not so high as the ridge 4. The outer surface of the mound 6 has applied thereto, as aided by its shape, a round spot of metallic-lustre enamel, which as shown in Fig. 1, may be an applied coat of a bronze-powder or lustre flake in an appropriate varnish, such as a solution of celluloid in amylaceate; but it will be understood that any du- 100 105 110

rable metallic lustre paint will serve, whether the fluid binder is a soluble or a fusible adhesive. In some cases, I prefer the metallic body to be of silver or aluminium powder or flakes, and I intend to refer to any of these metallic paints or enamels by the term "lustre enamel."

A button of the same form as that illustrated in Fig. 1 may be constructed with 10 many of the same advantages, as shown in Fig. 2, by coating the mound 6 with a soluble or fusible adhesive 9 and applying thereto a round spot of foil 10 of a suitable non-oxidizing metal.

15 As shown in Fig. 3, I may form a button for the same purposes by providing a mound 12 in a central position having undercut edges 13 over which a thin metal cap 14 of suitable dimensions is sprung. The whole 20 button, in each of these instances, or the central spot, may be lacquered or varnished after application of the lustrous spot.

In each of the above cases, the button is provided with the usual loop-shank consisting of a piece of wire 15, which may be bent 25 in the form shown, and having its divergent ends 16 embedded in the substance 1 of the button.

It will be observed that the appearance

of the old-art button of Fig. 5 is closely imitated by the new device, without weakening its structure; as is the case when the short-shank pin 17 of Fig. 6 is employed, as heretofore, to imitate the appearance of the headed shank.

The central spot in the button is protected from wear by the ridge 4, its lustre being as durable as that of the head of a metallic shank.

What I claim is:

1. A button comprising a body having an integral contour presenting an annular ridge and a central mound wholly within and beneath the plane defined by the said annular ridge having thereon a lustrous metallic 45 coating, the button being provided with a loop shank having its ends embedded in the substance thereof.

2. A button having a molded composition body with an annular face ridge and central 50 mound, the mound having thereon a coating of lustre enamel, and the body having embedded therein the ends of a wire loop shank, said ends extending into the thick parts of the button constituting said ridge.

Signed by me at Portsmouth, New Hampshire, this sixth day of January, 1921.

TIMOTHY DONOVAN.
